Stephen Barber of Norwich Connecticut
Letters Patent.

The Schedule referred to in these Letters Patent and making part
of the same containing a description in the words of the said Stephen
Barber himself of his improvement in tiltting Wagons.

To all to whom these presents shall come. Be it known that
I Stephen Barber of Norwich in the County of New London and State
of Connecticut have invented a new and useful improvement in
Wagons, Carriages and that the following is a full and exact descrip-
tion thereof, to wit, three or four Bars or strips of wood rest upon
the axles of said Wagon parallel to each other, upon said bars
the Body rests upon rollers. The body being moved backward on
said rollers along said parallel bars a sufficient distance, tilts
up. To prevent its rolling forward after it is rolled back, &
before it tilts, a piece of metal inserted into the front part of the
body falls upon the teeth of a piece of iron fastened upon one of said
parallel bars. The body is fastened down in front by hooks or
bolts, and also in rear. As the Body moves backward hooks
placed underneath the body catch upon a bar of metal running
along rear and parallel to the rear axle, to prevent it from run-
ning too far back. To prevent the body from moving sideways
in front from the line of said parallel bars, as it moves back-
wards a slat or bar, is attached perpendicularly on each side
of the forward part of the body running down below the body. The
body is thrown back by a lever or draw. The rollers move in grooves
in said bars. That I claim as my own invention and not pre-
viously known in the above described machine is the invention
and application of the rollers moving in said groove.
